UNITED STATES PATENT OFFICE.

GEORGE MALPASS, OF PHILADELPHIA, PENNSYLVANIA.

PEN-GRINDING MACHINE.

No. 845,006.

Specification of Letters Patent.

Patented Feb. 19, 1907.

Application filed October 3, 1905. Serial No. 281,116.

To all whom it may concern:

Be it known that I, GEORGE MALPASS, a citizen of the United States, residing at Philadelphia, county of Philadelphia, and State of Pennsylvania, have invented a certain new and useful Improvement in Pen-Grinding Machines, of which the following is a specification.

My invention relates to a new and useful improvement in pen-grinding machines, and has for its object to provide a machine for grinding the back of pen-points much more quickly and effectively than the same can be done by hand, and at the same time rock the pen-point back and forth concentric with its curved surface, so that the back of the pen-point will be evenly ground and all of the pens will be ground uniformly.

With these ends in view this invention consists in the details of construction and combination of elements hereinafter set forth and then specifically designated by the claims.

In order that those skilled in the art to which this invention appertains may understand how to make and use the same, the construction and operation will now be described in detail, reference being had to the accompanying drawings, forming a part of this specification, in which—

Figure 1 is a plan view of my improved pen-grinding machine; Fig. 2, an enlarged longitudinal section through one of the pen-holders; Fig. 3, a section taken on the line 3 of Fig. 1.

It is a well-known fact that in order to have the ink flow freely upon a steel pen the back of the same must be ground by means of an emery-wheel. This has heretofore been accomplished by holding the convex surface of the back of the pen against the periphery of a revolving emery-wheel and turning the pen by hand until the back is properly ground; but this process requires skilled labor and is comparatively slow. The machine which is the subject of this application will grind the back of the pen uniformly and much more effectively and quickly than can be done by hand, and I will now describe the operation of the machine in detail.

A represents the frame of the machine, which may be of any suitable shape or design, and secured in the standard A', arising from the frame of the machine, is a horizontal axle B, upon which is journaled a rotary pen-carrier C, adapted to be rotated intermit-

tently by means which will be hereinafter described. This rotary pen-carrier consists of two plates C' and C'', arranged a slight distance apart and secured one to the other. 60 Arranged around the periphery of the pen-carrier at equal distance apart are pen-holding devices, each of which are identically the same and each consisting of a tubular shaft D, extending through the two plates C' and C'' of the carrier and being journaled therein.

Upon one end of the tubular shaft D outside of the plate C'' is arranged a bifurcated bearing D', and between the two prongs of the bifurcated bearing D' is arranged the two 70 pen-holding jaws E. These pen-holding jaws E are both identically the same and are on the principle of a pair of pincers, the tail or inner end of the jaws being crossed and pivoted together, the same pivot which pivots the jaws together also extending through the prongs of the bifurcated bearing D'. The jaws are normally held together by means of springs F, arranged upon each side of the jaws, one end of each spring being connected 75 to one jaw and the other end to the other jaw. These springs also hold the inner end or tail pieces of the jaws in contact with one another, and it will be seen that if the inner ends of the jaws are spread apart the outer 80 end or pen-holding portion of the jaws will also be spread. For the purpose of spreading or opening these jaws at predetermined times I provide the plungers G, which are adapted to slide longitudinally through the 90 tubular shaft D, the inner end of these plungers being wedge shape, as indicated at G', and when pressed inward will enter between the tail ends of the jaws E and spread them apart. Secured upon the tubular shaft D in 95 between the plates C' and C'' are the gears H.

I represents the emery-wheel, which is adapted to be revolved on a horizontal axle by any suitable means, here shown as by a belt I'. This emery-wheel is so arranged 100 that the periphery of said wheel will come in contact with the back of a pen-point held in one of the pen-holding devices which is nearest to the emery-wheel. Thus the pen-carrier is revolved intermittently, and one after 105 the other of the pen-holding devices containing a pen is presented to the emery-wheel, and the pen-carrier rests a certain length of time between each of these intermittent movements, and while the pen is in contact 110 with the rotating emery-wheel the pen-holding device is rocked backward and forward

through a certain number of degrees, so that the whole convex surface of the pen-point will be brought into contact with the emery-wheel. This rocking movement I accomplish by means of a vertically-sliding reciprocated rack-bar J, which is adapted to slide in suitable bearings arising from the frame of the machine. As each pen-holding device comes into position, so that the pen it carries is brought in contact with the emery-wheel, the gear-wheel H, secured to the tubular shaft D of this particular pen-holding device, also comes in mesh with the constantly-reciprocating rack-bar J, and as this rack-bar J is reciprocated vertically it will be seen that the pen-holding device will be rocked backward and forward upon the tubular shaft D and all parts of the convex surface of the pen-point will be presented to the emery-wheel. In order that the pen-point may be held in spring contact with the emery-wheel, I provide the springs K, one for each pen-holding device, one end of the spring being attached to the bifurcated bearing D' and the other end to the jaws, so that the spring tends to rock the jaws upon the pivot E' outward toward the emery-wheel.

L represents the power-shaft, which is journaled in suitable bearings in the framework of the machine, and this shaft may be driven from any suitable source of power, preferably by means of a belt passing around the fast and loose pulleys L'.

M is a gear-wheel secured upon the power-shaft L, which meshes with the gear-wheel N, secured upon a counter-shaft N', also journaled in the framework of the machine.

O is a ratchet-wheel secured to the pen-carrier C and provided with as many teeth or notches as there are pen-holding devices upon the carrier.

P is a lever pivoted upon the shaft B and provided with the pawl P', adapted to engage the ratchet-wheel O.

Q is a link connected at one end to the lever P and at its lower end to a lever R, pivoted to the framework of the machine. This lever R is provided with a roller R', adapted to be held in contact, by means of a spring R'', with the cam S, secured upon the shaft N'.

Thus each time the cam S rotates, so as to rock the lever R, the lever P will be rocked, and the pawl P', engaging the ratchet-wheel O, will move the pen-carrier one step. In

order to prevent the pen-carrier from moving farther than the predetermined distance at each step, the plate C' is provided with notches C'', and the pawl C'', pivoted to the framework of the machine, is adapted to engage said notches, the pawl being disengaged from the notches each time the pen-carrier is about to be moved by means of a cam T, secured upon the shaft L, engaging the tail end of the pawl C''.

U is a small gear-wheel journaled in suit-

able bearings secured to the framework of the machine, and this gear-wheel meshes with the gear-wheel M, and upon the same shaft as the gear-wheel U is a crank-disk U', to which the lower end of the link U'' is eccentrically connected. The upper end of said link U'' is connected to the reciprocating rack-bar J, and as the crank-disk U' is revolved the rack-bar is reciprocated.

As the periphery of the emery-wheel I cannot be made to conform exactly to the shape of the pen-point, it is desirable to move the emery-wheel as the grinding is being done, so that instead of grinding away a line upon the pen a considerable length of surface will be ground, and the length of the surface ground will depend upon the movement given the emery-wheel. To accomplish this oscillating movement of the emery-wheel, I provide a plate V, adapted to rest upon the top of the framework of the machine, and this plate V is pivoted to the framework of the machine coincident with and directly below the point where the periphery of the emery-wheel touches the convex surface of the pen-point, as will be seen in Fig. 1. Arising from the plate V are the standards V', in the upper ends of which the emery-wheel is journaled. The plate V is journaled to the framework of the machine by means of an adjustable bearing consisting of a slide-bar W, mounted to slide laterally in a suitable guideway secured to the frame of the machine, and thus the pivotal point of the plate V can be adjusted toward or away from the pen-carrier, as desired.

In order to oscillate the plate V so as to move the emery-wheel, I provide a lever X, pivoted intermediate of its two ends to the framework of the machine, one end being pivoted to the plate V and the other end being provided with a roller X', lying within the groove of a cam Y, which cam is secured to the power-shaft L. This cam Y is so constructed as to oscillate the plate V in the proper manner, so that the emery-wheel will grind the back of the pen-point the required distance.

In order to hold the pen-carrying devices always radial when the gears H are in contact with the rack-bar J, I provide for each pen-holding device the two levers Z, each lever being pivoted to the plate C' at one end, the free end of the levers coming upon each side of a projection extending inward from the bifurcated bearing D'. The free end of these levers Z is held in tight contact upon each side of the projection before mentioned by means of the springs a, and this the tension of the springs upon each side of the projection serves to always hold the pen-holding devices in their proper radial position.

In the operation of the machine as the pen-carrier revolves the jaws of one set of pen-holding devices are opened at a predeter-

mined point before the emery-wheel has been reached, so that the operator may insert a pen-point in between the jaws, and the jaws are again opened at a predetermined point 5 after the pen has been ground, so that the pen-point can fall therefrom in a suitable receptacle for the same. This opening of the jaws can be accomplished at any point desired; but the jaws are adapted to be opened to receive the pen-point at the point 1 in Fig. 3 and are adapted to be opened to release the pen at the point 2 in Fig. 3. The opening of the jaws, as before described, is accomplished by the pressing inward of the plungers G, and this can be done by any suitable means, either by means of stationary cams or movable cams operating suitable levers. In the drawings both ways are shown, as the stationary cam b, secured to the framework 20 of the machine, as shown in Fig. 1, is utilized for opening the jaws to receive the pen-point, and a lever e, operated by a cam upon the back of the cam S, is utilized for opening the jaws to release the pen-point. As the 25 springs K tend to throw the jaws outward toward the periphery of the pen-carrier, the pen-points would be brought into contact with the grinding-wheel too early if some provision was not made to guard against this. 30 Therefore I provide a shield f, which extends over the edge of the grinding-wheel just above the point where the grinding is done, as shown in Fig. 3. This shield is supported from the frame of the machine; and when the 35 pen-carrier rotates the pen will come in contact with this shield and will not come in contact with the grinding-wheel until it passes from off the lower end of the shield, and then the pen is in the proper position for grinding. 40 As seen in Fig. 1, the support which supports the shield f extends for a short distance parallel with the pen-carrier, as shown at g. This portion g is arranged in such a position that if the pens have not been fully inserted 45 within the jaws this portion g will either push them into their proper position or if they are out too far the pens will strike this portion g and be thrown out of the machine before any grinding is done, so that they can be again 50 inserted properly without wasting the pens. It will thus be seen that in the operation of this machine no skilled labor is required, it being only necessary for the operator to insert a pen-point in the open jaws at the point 55 1 at each step in the revolution of the pen-carrier. Of course this feeding of the pens could be accomplished automatically; but that forms no part of this invention. As soon as the pen-point is inserted between the 60 open jaws the next time the carrier revolves the jaws instantly close as the plunger G runs off the cam b, and the pen-point is carried around step by step until it comes in contact with the emery-wheel, where it is rocked and 65 the convex surface is ground, and then on a

continued movement of the carrier when a certain point is reached the jaws are automatically opened and the pen-point released.

It will thus be seen that the machine is entirely automatic and that each pen-point is 70 ground uniformly, exactly the same length of surface being ground each time, and can be done in one-third of the time required to accomplish it in the old way by hand.

Of course I do not wish to be limited to the 75 exact construction here shown, as slight modifications could be made without departing from the spirit of my invention.

Having thus fully described my invention, what I claim as new and useful is— 80

1. In a pen-grinding machine, a rotary grinding-wheel, a pen-holding device adapted to hold the convex surface of the pen-point in spring contact with the grinding-wheel, the pen-holding device consisting of spring- 85 actuated jaws grasping the pen, means for automatically spreading these jaws at predetermined times for the insertion and release of the pen, and means for rocking the pen-holding device while the pen is in contact with the grinding-wheel.

2. In a pen-grinding machine, a rotary grinding-wheel, a pen-carrier, two or more pen-holding devices arranged upon the pen-carrier, means for moving the carrier intermittently so that the pen-holding devices are brought successively into such a position that the convex surface of the pen-point held in the pen-holding device will come in contact with the grinding-wheel, means for rocking the pen-holding device which holds the pen being ground while said pen is in contact with the grinding-wheel, and means for automatically releasing the pen after the 95 same is ground. 100

3. In a pen-grinding machine, a rotary grinding-wheel, a pen-carrier, a series of pen-holding devices arranged upon the carrier at equal distances apart, each pen-holding device consisting of a pair of spring-closed 110 jaws adapted to grasp the pen, means for moving the carrier intermittently so as to bring the pen-holding devices successively in such a position that the convex surface of the pen will come in contact with the periphery of the grinding-wheel, means for rocking the pen-holding device while the pen is being ground so that the whole of the convex surface is presented to the grinding-wheel, 115 means for automatically spreading the jaws at predetermined times for the insertion of the pen and the release of the same, and means for oscillating the grinding-wheel laterally, the pivotal point from which said wheel oscillates being coincident with the 120 point where the periphery of the grinding-wheel touches the pen while grinding.

4. In a machine of the character described, a rotary grinding-wheel, a pen-carrier provided with a series of pen-holding devices, 130

means for moving said pen-carrier intermittently so as to successively bring the convex surface of the pen-points held by the pen-holding devices into contact with the periphery of the grinding-wheel, means for rocking the pen-holding device during the time the pen is being ground, a movable bearing-frame in which the grinding-wheel is journaled, a main frame of the machine, the movable bearing-frame being pivoted to the main frame at a point coincident with the point where the grinding-wheel touches the pen being ground, and means for oscillating the movable bearing-frame and grinding-wheel in a line parallel with the shaft of the grinding-wheel.

5. In a pen-grinding machine, a main frame, a rotary grinding-wheel adapted to be constantly revolved, a rotary pen-carrier journaled in suitable bearings in the main frame, a series of pen-holding devices arranged upon the carrier near the periphery of the same equal distances apart, each pen-holding device consisting of a pair of spring-actuated jaws adapted to grasp the pen, said jaws being journaled in the carrier, means for moving the carrier intermittently so as to bring the convex surface of the pen held in the pen-holding devices successively against the periphery of the grinding-wheel, means for rocking the pen-holding devices while the pen is being ground so that the whole of the convex surface will be brought in contact with the grinding-wheel, means for holding the pen in spring contact with the grinding-wheel, means for holding the pen-holding devices in their normal position when not being rocked, means for automatically opening the jaws at predetermined times for the insertion and releasing of the pens, means for oscillating the grinding-wheel in a plane parallel with its shaft, the pivotal point from which the same oscillates being coincident with the point of contact of the grinding-wheel and pen being ground.

6. In a machine of the character described, a rotary grinding-wheel, a pen-carrier in combination therewith adapted to carry the pens and successively bring the convex surface of said pens into spring contact with the periphery of the grinding-wheel, a main frame, a movable bearing-frame in which the grinding-wheel is journaled, the movable frame being adjustably pivoted to the main frame at a point coincident with the point of contact of the grinding-wheel and pen-point, means for oscillating the movable frame and grinding-wheel in a line parallel with the shaft of the grinding-wheel.

7. In a pen-grinding machine, the combination with a rotary grinding-wheel of a rotary pen-carrier, said pen-carrier consisting of a plate, a series of pen-holding devices carried by the plate at equal distances apart, each pen-holding device consisting of a pair

of spring-actuated jaws adapted to grasp the pen, a bearing for the jaws journaled in the pen-carrier plate by extending transversely therethrough, the jaws being pivoted together and also pivoted to the bearing, spring means for holding the pen-holding devices in their normal position and still at the same time allowing them to be rocked, means for intermittently revolving the pen-carrier so as to bring the convex surface of the pen-points held in the jaws successively against the periphery of the grinding-wheel, springs tending always to force the jaws holding the pens toward the periphery of the pen-carrier plate so that the pens will be held in spring contact with the grinding-wheel, means for automatically opening the jaws at predetermined times, a gear-wheel secured upon the shaft of each pen-holding device, which shaft passes through the pen-carrying plate, a reciprocating rack-bar, means for constantly reciprocating said rack-bar, said rack-bar so located that the gear-wheel of the pen-holding device will be brought in mesh with the same at the same time the pen-point is brought in contact with the grinding-wheel so that the reciprocation of the rack-bar will rock the gear-wheel and consequently rock the pen-point, means for automatically locking the pen-carrier while it is stationary and unlocking the same just previous to the time when it is to be moved, as specified.

8. In a pen-grinding machine, a constantly-revolving and constantly-oscillating grinding-wheel, in combination with a rotary pen-carrier adapted to successively bring the convex surfaces of the pens against the periphery of the grinding-wheel, said pen-carrier consisting of two disk-shaped plates secured together and journaled in suitable bearings parallel with the shaft of the grinding-wheel, a series of pen-holding devices arranged upon the carrier, each pen-holding device consisting of a bifurcated bearing secured upon the end of a tubular shaft, said tubular shaft extending transversely through the plates of the carrier and being journaled therein, a gear-wheel secured upon the tubular shaft between the plates, a pair of jaws pivoted between the prongs of the bifurcated bearing, said jaws consisting of two crossed levers, said levers being pivoted together upon the same pivot which pivots them to the bearing, springs tending to hold the jaws closed so that the pen will be grasped by a spring-pressure, a spring secured at one end to the bifurcated bearing and at the other end to the jaws tending to rock the jaws outward toward the periphery of the carrier, a plunger adapted to slide within the tubular shaft, one end of the plunger normally extending beyond the tubular shaft, the inner end of the plunger being formed wedge shape and adapted to enter between the heel end of

the crossed levers forming the jaws so as to spread the jaws when the plunger is pressed inward, means for limiting the movement of the plunger, means for pressing the plunger inward at predetermined times to open the jaws, spring means for holding the jaws radial and at the same time allow them to be rocked upon the shaft, a constantly-reciprocating rack-bar with which the gear-wheels of the pen-holding devices are adapted to mesh when the pen-point is brought in contact with the grinding-wheel, as specified.

9. In a pen-grinding machine, a constantly-revolving and laterally-oscillating grinding-wheel, an intermittently-moved pen-carrier, pen-holding devices arranged upon the carrier, the pens held in the pen-holding devices adapted to be successively brought in contact with the grinding-wheel and rocked while in contact, in combination with the

mechanism for accomplishing the various movements of the machine.

10. In a pen-grinding machine, the combination of an intermittently-moving pen-carrier and rotating grinding-wheel and pen-holding devices adapted to hold the pens in spring contact with the grinding-wheel, with means for preventing the pen from coming in contact with the grinding-wheel until the proper time for grinding, and means for removing the pens from the jaws if they have not been properly inserted or for pushing them into the jaws in their proper position.

In witness whereof I have hereunto affixed my signature in the presence of two subscribing witnesses.

GEORGE MALPASS.
